UNITED STATES PATENT OFFICE.

CHARLES TURNER AND HARRY J. FLOOD, OF CHICAGO, ILLINOIS; SAID FLOOD
ASSIGNOR TO SAID TURNER.

OIL-EXTRACTING DEVICE.

1,024,230.

Specification of Letters Patent. Patented Apr. 23, 1912.

Application filed June 5, 1911. Serial No. 831,440.

To all whom it may concern:

Be it known that we, CHARLES TURNER and HARRY J. FLOOD, citizens of the United States, and residents of Chicago, county of Cook, and State of Illinois, have invented certain new and useful Improvements in Oil-Extracting Devices, of which the following is a specification, and which are illustrated in the accompanying drawings, forming a part thereof.

The invention relates to an apparatus for extracting oil from garbage and other materials and to that type of device in which the oil is extracted by the use of a solvent, the operation being carried on continuously, the material to be treated being delivered to and discharged from the machine without interruption.

The objects of the invention are to generally improve devices of this character, simplifying the action and securing an increased efficiency.

The character of the invention is fully hereinafter pointed out and is shown in the accompanying drawings in which—

Figure 1 is a longitudinal vertical section of the machine as mounted in a building, some of the auxiliary parts being shown in elevation, Fig. 2 is a detail longitudinal vertical section of the apparatus some parts being shown in elevation, Fig. 3 is a sectional detail of a safety vent used in the machine, Fig. 4 is a rear end elevation, some of the parts being broken away, and Fig. 5 is a front end elevation, some of the parts being broken away.

The apparatus consists generally of a series of cylinders set at an incline and through which the material to be treated is driven by means of spiral conveyers and within which it is successively treated for washing out the oils by means of a solvent such as gasolene, rewashing for the purpose of securing any oils which may have escaped the first operation and steamed for the purpose of recovering any of the solvent which may have remained in the material after the rewashing. The material is fed to the lower end of the first cylinder through a hopper and as it is moved through this cylinder by the action of the conveyer, is washed by the solvent which is delivered to it through perforations in the conveyer shaft, the oil and solvent escaping

from the cylinder through numerous small 55 perforations in its wall to a receiving jacket within which the cylinder is inclosed and from which they are drained to a suitable receptacle. The drain pipe is so located that the liquid accumulates within the 60 jacket and the lower end of the cylinder to a level above the throat of the hopper thus constituting a liquid seal for preventing the escape of vapors through the hopper. From the upper end of the first cyl- 65 inder the material falls through a connecting pipe to the lower end of the second cylinder through which it is passed and treated in similar manner, a liquid seal being there maintained if found desirable for preventing vapors from passing back into the first cylinder. From the upper end of the second cylinder the material falls through a connecting pipe into the lower end of the third cylinder through which it is passed 70 in the same manner and from which it is discharged through a discharge pipe. In the third cylinder there is forced into the material through a hollow and freely perforated shaft of the conveyer, live steam 80 which vaporizes any of the solvent which may have been carried over from the second cylinder, the vapors escaping from the inclosing jacket through pipes leading to a suitable condenser. In order to prevent vapors from passing back from the third cyl- 85 inder into the second an annular series of fine steam jets are delivered into the pipe connecting these two cylinders being directed obliquely downward and in order to prevent the escape of vapors through the discharging nipple a similar series of steam jets enter this nipple being directed obliquely upward.

The receiving hopper is shown at 10 and 95 as delivering at 11 to the lower end of the cylinder 12 which is inclined upwardly, as shown, at an angle of about twenty degrees. This cylinder is inclosed through the major portion of its length within a jacket 13, the 100 inclosed portion of the cylinder being freely perforated, as indicated at 14. A spiral conveyer 15 is located within the cylinder 12, extending throughout its entire length and being fixed upon a tubular shaft 16 105 journaled in the ends of the cylinder. A pipe 17 leads to the upper end of the shaft 16 with which it is connected by means of a

stuffing box 18. A solvent material such as gasolene is delivered to the shaft through the pipe 17 and from the shaft to the interior of the cylinder through numerous fine 5 perforations indicated at 19. The solvent together with the oils washed out of the material escape from the cylinder through the perforations 14 into the jacket 13 from which they are discharged through a pipe 10 20 communicating with a receiving tank 21. The pipe 20 is connected with the jacket 13 at a point slightly above the throat of the hopper 11 and as a consequence the liquids accumulate within the lower end of the 15 jacket and cylinder so as to seal the hopper throat. The pipe 20 is provided with a valve as indicated at 22, by means of which the discharge of the liquids may be retarded thus raising their level within the jacket 20 and cylinder. Drain pipes 23, 24 lead from the jacket 13 at lower levels than the pipe 20 and afford means for completely discharging the jacket and cylinder of their liquid contents. These drain pipes are provided with valves as indicated at 25, 26. A 25 drain pipe 27 having a valve 28 leads from the extreme lower end of the cylinder 12. All of the drain pipes are shown as communicating with the tank 21.

30 From the lower side of the upper end of the cylinder 12 there leads a pipe 29 through which the material is discharged into the lower end of the second cylinder 30 which with its accessories may be an exact duplicate of the cylinder 12, there being present a spiral conveyer 31 mounted on a hollow shaft 32 journaled in the ends of the cylinder and having numerous fine perforations 33 opening to the interior of the cylinder; a 35 jacket 34 inclosing the cylinder through a major portion of its length, the portion of the wall of the cylinder which is thus inclosed, being freely perforated as indicated at 35; a pipe 36 for delivering the solvent liquid to the upper end of the shaft 32; a 40 discharge pipe 37, drain pipes 38, 39 and 40, all provided with valves and leading from the jacket 34 and the cylinder 30 to a receiving tank 40^a.

45 From the lower side of the upper end of the cylinder 30 there leads a pipe 41 for delivering the material to the lower end of the third cylinder 42. This cylinder with its accessories differs but slightly from the cylinders 12 and 30, being inclosed through the major portion of this length within a jacket 43 and there being within it a spiral conveyer 44 fixed upon a tubular shaft 45 to the upper end of which there leads a pipe 46 and which is freely perforated, as shown at 47, to discharge into the cylinder 42. Drain pipes 48, 49 lead respectively from the lower ends of the jacket 43 and cylinder 42 to a receiving tank 50 and a header 51 50 communicates with the chamber of the

jacket 43 by means of a plurality of nipples, as 52, 53 and 54 which lead through the upper side of the wall of the jacket, a pipe 55 leading from the header 51 to a condensing coil 56. A pipe 57 leads from the lower 70 side of the cylinder 42 at its upper end. A hollow belt 58 encircles the pipe 41 and to this belt there leads a pipe 59. An annular series of downwardly inclined ports 60 lead from the chamber of the belt 58 into the 75 chamber of the pipe 41 adjacent the lower end of the latter. A hollow belt 61 encircles the pipe 57, a pipe 62 leads to the chamber of the belt and an annular series of upwardly inclined ports 63 lead from the 80 chamber of the belt to the chamber of the pipe 57, entering it near its upper end.

The conveyers of the several cylinders are driven by means of a belt pulley 64 mounted upon a shaft 65 carrying pinions 66, 67 and 68 meshing with gear wheels 69, 70 and 71 fixed respectively upon the shafts 16, 32 and 45.

The solvent is supplied to the cylinder 12 through the pipe 17 by means of a pump, 90 conventionally shown at 72, the pump drawing from any suitable reservoir. In practice it is feasible to regard the tank 40^a as the source of supply and in the drawings the suction side of the pump is shown as being connected with this reservoir by means of the pipe 73.

The liquid discharged from the cylinder 12 is received in the tank 21 and consists of an admixture of gasolene, oil and considerable refuse matter. The oils separate out to some extent and float on the gasolene. An overflow pipe 74 leads from this tank to a vaporizer 75 of any desirable construction where the volatile solvent which has been carried over with the oils is vaporized and passes through the pipe 76 to the coil 56, and thence through the pipe 77 to the receiving tank 78. The oils and the refuse carried by them escape from the vaporizer 75 through a pipe 79 to a suitable separator represented at 80.

The solvent for the re-wash of the material is fed to the cylinder 30 from the tank 78 by means of a pump 81 connected therewith on its suction side by the pipe 82 and delivering through the pipe 36. The liquids discharged from the cylinder 30 are received in the tank 40^a. From this tank there leads an overflow pipe 83 to the vaporizer 75 for 120 carrying off such of the oils as may rise to the top. The solvent accumulated in this tank is sufficiently pure for use in the primary washing which occurs in the cylinder 12.

125 Steam is carried to the tubular shaft 45 and to the hollow belts 58 and 61 from any suitable source of supply through the pipes 46, 59 and 62 respectively. The vapors escaping through the perforations 47^a in the 130

cylinder 42 are, as has been stated, led to the coil 56 through the pipe 55. Any liquids which may accumulate in the jacket 43 are led therefrom by the pipe 48 to the tank 50 from which they are drained through the pipe 84 to the receiving tank 78, passing through a trap 85, of any approved form, where water, if any be present, is eliminated. Safety vents 86, 87 are provided for the cylinders 12 and 30 in order to eliminate any danger from explosions should a fire be accidentally developed within these cylinders. The cylinders themselves are made of sufficient strength to withstand a high degree of pressure. Each of the vents 86, 87 is closed by means of a frangible plate 88, preferably of glass, which will yield to a pressure much below that which the walls of the cylinders are capable of withstanding. The apparatus is shown in the drawings as being mounted in a building having two floors. The pumps, vaporizer, condenser, separator and final receiving tank are located in the lower compartment, the floor of which is represented at 89. These parts of the apparatus are in common use and form no part of the present invention.

The several cylinders and the tanks associated therewith are mounted upon the floor 90 of the upper compartment and are carried by any suitable frame, as 91, more plainly shown in Figs. 4 and 5. As this frame may be designed according to the judgment of the manufacturer, it need not be described in detail.

There may be associated with the cylinders 12 and 30 a glass gage for showing the level of the liquid within the cylinders. In Fig. 5 such a gage 92 is associated with the cylinder 12.

In the washing operation the solvent is not only discharged through the material radially but by reason of the inclined position of the cylinders it gravitates downwardly through the mass toward the lower end of the cylinder and its action in the material is thereby prolonged.

We claim as our invention—

1. In an oil extracting device, in combination, an inclined cylinder, a jacket inclosing a portion of the cylinder, the cylinder walls inclosed within the jacket being foraminous, a hopper delivering to the lower end of the cylinder, a conveyer for advancing material upwardly through the cylinder, means for introducing a solvent into the cylinder and a drain pipe leading from the jacket at a

point elevated above the connection of the hopper with the cylinder.

2. In an oil extracting device, in combination, an inclined cylinder, a jacket inclosing a portion of the cylinder, the portion of the cylinder walls inclosed within the jacket being foraminous, a hopper delivering to the lower end of the cylinder, a tubular shaft 65 mounted on the axis of the cylinder and having lateral perforations, a spiral conveyer carried by the shaft, means for delivering a solvent to the upper end of the shaft and a drain pipe leading from the jacket at 70 a point above the connection of the hopper with the cylinder.

3. In an oil extracting device, in combination, a pair of inclined cylinders arranged in series, a feed hopper delivering to the lower 75 end of the cylinder first in the series, a pipe connecting the upper end of such cylinder with the lower end of the next cylinder, means for advancing material upwardly through each of the cylinders, means for introducing a solvent into each of the cylinders and drain pipes for conveying liquid from each of the cylinders and being so positioned as to maintain a level of liquid above the receiving opening at the lower 85 end thereof.

4. In an oil extracting device, in combination, a plurality of inclined cylinders arranged in series, a feed hopper delivering to the lower end of the first cylinder of the 90 series, tubular connections between each of the cylinders and the next succeeding cylinder in the series, a discharge spout at the upper end of the last cylinder of the series, means for conveying material upwardly 95 through each of the cylinders, means for delivering a solvent to the first and intermediate cylinders, means for draining liquids from such last named cylinders and for maintaining a level of liquid therein above 100 the receiving apertures at their lower ends, means for delivering steam to the last cylinder of the series, downwardly inclined nipples for delivering steam to the receiving aperture of such cylinder, upwardly inclined nipples for delivering steam into the discharging aperture at the upper end of the last named cylinder and means for conveying vapors laterally from said cylinder.
